UNITED STATES PATENT OFFICE.

ZDENKO FREUND, OF NEWARK, NEW JERSEY, ASSIGNOR TO THE TENCH STUDIOS, A CORPORATION OF NEW JERSEY.

DESIGN FOR A GEM.

Application filed November 29, 1926. Serial No. 19,866. Term of patent 14 years.

To all whom it may concern:

Be it known that I, ZDENKO FREUND, a citizen of the United States, and a resident of Newark, in the county of Essex and State of New Jersey, have invented a new, original, and ornamental Design for Gems, of which the following is a specification, drawing, forming part thereof.

Figure 1 is a plan view of a gem of my new design; Figure 2 is a side elevation of the gem; Figure 3 is an end elevation of the gem.

I claim:

The ornamental design for a gem, as reference being had to the accompanying shown.

ZDENKO FREUND.
